FIG. 7.

UNITED STATES PATENT OFFICE.

CORNELIUS B. CORCORAN, OF NEW YORK, N. Y., ASSIGNOR TO UNDERWOOD TYPE-WRITER COMPANY, OF NEW YORK, N. Y., A CORPORATION OF DELAWARE.

TYPE-WRITING MACHINE.

1,144,755.

Specification of Letters Patent. Patented June 29, 1915.

Application filed October 22, 1912. Serial No. 727,094

To all whom it may concern:

Be it known that I, CORNELIUS B. CORCORAN, a citizen of the United States, residing in New York, in the county of New York and State of New York, have invented certain new and useful Improvements in Type-Writing Machines, of which the following is a specification.

This invention relates to the paper-controlling devices and letter-space scales of typewriting machines, and one principal object is to provide means for facilitating the insertion and gaging of work-sheets.

When introducing work-sheets rearwardly with lower edge foremost at the front side of the platen of a front-strike writing machine, some difficulty has been encountered because of the usual arrangement of the ribbon-vibrator in front of the platen and almost in contact therewith. There is liability of the work-sheet fouling upon the ribbon vibrator, and to some extent the same is true of the usual center guide for the type-bars, which is arranged just below the printing point. As a means for overcoming this difficulty, I have arranged a paper-guiding chute or apron at the front of the platen, placed to one side of the machine so far as to be entirely to one side of both the type guide and the ribbon vibrator; so that, by running the carriage over say to the extreme limit of its leftward travel, the work-sheet may be conveniently introduced between the guiding-chute and the platen, and run backwardly around the under side of the platen, and then gripped by the feed rolls, whereupon the carriage may be returned to the right, to begin the line of writing. In this way all liability of fouling of the work-sheet upon the ribbon guide or the type guide is avoided. For the purpose of the invention, there may be used a carriage of super-width in proportion to the width of the work-sheet; or, in other words, a machine having an extra wide carriage may be employed for writing upon a sheet of ordinary size. This will permit the carriage to be set far enough to the left to permit the introduction in this way of a sheet of common size. The devices under the platen for guiding the work-sheet need to be only as wide as the sheet; and said chute may be of a length substantially equal to the length of the ordinary printing field on the platen. A wide-carriage machine may be readily employed for intro-

ducing and writing upon work-sheets of ordinary width, whenever it is desired to introduce the sheets at the front of the platen; and, whenever required, the same carriage can also be employed for writing in the ordinary way upon extra-wide sheets introduced in the usual manner at the rear of the platen. Said apron or chute may coöperate with guiding devices mounted on the carriage itself and extending around the under side of the platen to the front thereof; said guiding devices being normally close to the platen, but being releasable, so that they may be dropped to a position to coöperate with said chute. Said chute or guiding apron may be employed as a line gage for the sheet on the platen, and to this end may be hinged upon the framework of the machine, so as to swing up from its normal position to a position where it coincides to the printing line of the platen, thus facilitating the adjustment of the work-sheet on the carriage. This gage may also be provided with a numbered letter scale, which, when the carriage is at the extreme end of its run, will indicate correctly the position of the written letters on the work-sheet, and will hence at this time serve as an ordinary platen scale. It will also be understood that the ordinary scale and index may be retained for indicating the position of the carriage, and that this supplemental scale may be employed for the purpose of a scale, even if it is not employed as a paper-guiding chute.

In the Underwood front-strike typewriting machine to which the invention is herein illustrated as applied, the usual rolls may run upon the under surface of the platen, and these rolls may be released in the usual manner from the platen. At the same time that the rolls are released, the guiding plate or apron which curves around the under side of the platen is dropped down therefrom, so that the front edge of said plate is brought into register with the sloping deflector-plate or chute, which is arranged upon the machine frame, and preferably displaced entirely to one side of the printing point. By the aid of this chute the work-sheet may be dropped into the machine bottom edge foremost, and conducted around beneath the platen and up at the rear thereof.

Preferably the plate forming part of the chute is pivoted, and the edge thereof near-

est the platen has a scale thereon corresponding to the letter-spaces of the platen-escape-
ment mechanism. This plate is preferably arranged at such a height that when swung on its pivot toward the platen, its edge will 5 serve as a guide for positioning the work-
sheet, and at the same time the edge of this plate will indicate the bottom of the line of writing. The scale divisions on said plate 10 may be numbered so as to indicate what letter-spaces on the platen correspond to any given letter-space on the ordinary scale of the typewriter.

Other features and advantages will hereinafter appear.

15 In the accompanying drawings, Figure 1 is a perspective plan of an Underwood wide-carriage front-strike writing machine provided with the present improvements and showing the parts ready for the insertion of sheets at the front of the platen. Fig. 2 is a sectional side elevation showing the parts in their normal position when writing is being done. Fig. 3 is a view of the scale plate and margin stop of the wide-carriage machine. Fig. 4 is a view similar to Fig. 2, except that the bottom pressure rolls are released together with the paper-guiding apron for the insertion of work-sheets at 20 the front of the platen. Fig. 5 is a sectional side view similar to Fig. 4, but showing the swinging scale plate raised to indicate the line of writing. Fig. 6 is a perspective view of the parts seen in Fig. 5 taken from the 25 upper right-hand corner of said Fig. 5. Fig. 30 7 is a front view showing the line of writing as indicated by the present invention on the typewriter platen.

The cylindrical platen 1, which is shown 40 of extra length, although shorter platens may be used, is journaled by an axle 2 in the ends 3, 4 of a platen frame, which comprises a rear paper shelf 5 connecting said ends, and also comprises a tie-rod 6 extending 45 between said ends. The platen frame is mounted by suitable means, not shown, upon a carriage 7 which runs upon the usual forward and rear tracks 8, 9.

The system of pressure rolls running upon 50 the under side of the platen to carry the work sheet around the same may be of the usual construction, comprising rear rolls 10 mounted on shaft 11, and front rolls 12 mounted on shaft 13; shaft 11 being carried 55 on arms 14, and shaft 13 being carried on arms 15; all of said arms journaled on tie-rod 6. Upon said rod 6 are also mounted leaf springs 16, 17, to engage respectively the arms 14, 15, whereby the rolls 10, 12 are 60 pressed against the platen. The pressure rolls may be released in the usual manner by means of a key 18 pivoted at 19 on the platen frame and connected by a link 20 to an arm 21 on rock shaft 22, which is journaled 65 on the platen frame and extends along

the platen between arms 23 formed on said roll-carrying arms 14, 15; the arms 23 normally occupying recesses 24. When said rock shaft 22 is rotated, the arms 23 are forced apart, as at Fig. 4, thus pulling down 70 the arms 14, 15, together with the rolls 10, 12, and leaving a clearance between said rolls and the platen 1 for the introduction and adjustment of the work-sheets. Owing to the cylindrical shape of the shaft 22, the 75 arms 23 are mechanically locked apart in their released positions at Fig. 4.

When the parts are in the position seen in Fig. 4, a work-sheet 25 may be inserted from the front of the machine by passing it over 80 the plate 26, which is mounted on the front of the machine and forms a chute for said work-sheet. From said chute the work-sheet passes over the front fingers 27 of an apron 28, which is arranged to move with the pressure rolls 10 and 12 to and from the platen. This apron extends rearwardly so as to overlap to some extent the paper-table 5 and guides the rearwardly moving sheet on to said paper-table. Said work-sheet may be clamped to move with the revolving platen, as seen in Fig. 2, by swinging the handle 18 upwardly so as to cause the rolls 10 and 12 to bear against the platen, and the paper 90 apron 28 is caused to move up with the rolls 95 by means of an auxiliary roll 29 on the shaft 13 overlapping said apron. The apron 28 is moved downward with the rolls by means of a hooked arm 28^a formed as an extension of said apron and catching under arm 15 carrying roll 12. Before so clamping the work-sheet against the platen, the work-sheet may be adjusted in position so as to 100 properly center it in the writing line by swinging the plate 26 upwardly by means of its handle 30, till its handle hits a fixed lug 30^a, so that the edge of said plate, as seen in Fig. 5, is adjacent the platen. This edge is so set that it indicates or gages the bottom of a line of writing, as said writing appears 110 when on the work-sheet; and after the work-sheet has been manually adjusted to the desired point, it may be clamped in position as aforesaid by raising the handle 18.

The plate 26 also carries a scale of letter-spaces along its edge, which spaces are numbered from left to right, as seen in Fig. 6, and the zero point of said scale is so set that when the typewriter carriage, as seen in said figure, is at the extreme left-hand of its movement, said zero point will indicate the initial printing point on said work-sheet, that is, the printing point when the platen is returned to the extreme right to the beginning of the line. Also a work-sheet may be 120 positioned by means of said scale to correspond to any other initial printing point on the platen; and such point may be determined by a margin stop.

125 Writing is done on the work sheet on the 130

platens 1 in the ordinary manner by means of type 31 pivotally mounted in a segment 32 and which are moved upwardly and rearwardly to strike against said platen by means of keys, not shown, and in so moving, operate the usual escapement devices for feeding the carriage to the left in the usual manner. The position of the printing point on said carriage 7 is indicated by a pointer 18 33 fast on said carriage, coöperating with a scale plate 34 fast on the front of the machine.

The swinging scale plate 26 is pivotally mounted by means of pins 35 on a bar 36 extending leftwardly from a cross bar 37 forming part of the usual frame of the typewriting machine. Said bar 36 embraces a lug 38 on said bar 37 by means of screws 39 threaded through arms 40 of said bar 36, 20 and may be raised on the bar 37 by means of a screw 41 bearing against said bar 37. It is tightened down against said bar by means of a screw 42 threaded into the top of said lug 38. The bar 36, which carries the scale plate 26, is steadied at its outer end by means of a bracket 43 on the bar 36 intermediate its ends and extending toward a plate 44 fast in the frame of the machine, the bracket 43 being adjustably fastened to said 25 plate 44 by means of screws 45 extending through slots 46 in said plate. The fixed lug 30^a forms an extension of said bar 36.

The pins 35 carrying the plate 26 are not fastened directly to said bar 36, but are carried by lugs 47 forming extensions of a plate 48 fast on the bar 36 and secured thereto by screws 49. Said bar 36 also carries an L bar 50 on outwardly extending arms 51 of said bar. The plate 26 is normally drawn downward so as to lie against said arms 51 by means of a spring 52, so that the surface of the plate 26 forms a continuation of the upper arm of said L bar 50.

To illustrate the use of scale 26 as a correct platen scale when the carriage is in its extreme left-hand position, there is shown (at Fig. 3) a right-hand margin stop 53 comprising a pointer 55 and a handle 54 for shifting the stop, and said stop is, for 45 the purposes of illustration in the present invention, located at the tenth division on the scale 34. The exact location of said tenth space is shown on the work-sheet by the corresponding scale division on the 50 scale plate 26 when the work-sheet is being inserted. In this way, the writing may be accurately registered with any rulings that may exist on the work-sheet.

Variations may be resorted to within the 55 scope of the invention, and portions of the improvements may be used without others.

Having thus described my invention, I claim.

1. In a front-strike typewriting machine, 60 the combination with a frame and a carriage

thereon, of a rotatable platen on said carriage, a paper apron thereunder, means for moving said apron away from said platen, and a swinging guide inclined downward from its pivot in position to guide a work-sheet onto said apron when away from said platen, and movable about its pivot to bring its free edge to the platen at the printing line. 70

2. In a front-strike typewriting machine, 75 the combination with a frame and a carriage thereon, of a rotatable platen on said carriage, a paper apron thereunder, means for moving said apron away from said platen, a pivoted guide extending downward from its pivot in position to guide a work-sheet onto 80 said apron, and a handle for swinging said guide to bring its free edge into position to indicate the printing line.

3. In a front-strike typewriting machine, 35 the combination with a frame and a carriage thereon, of a rotatable platen on said carriage, a paper apron thereunder, means for moving said apron away from said platen, a pivoted guide depending from its pivot to 90 guide a work-sheet onto said apron, a handle for swinging said guide to bring its lower edge up to the printing line on the platen, and an indicator on said guide to show the position of a letter space on the 95 work-sheet.

4. In a front-strike typewriting machine, the combination with a right-hand margin stop, of a scale on the frame of the machine at the left for indicating the position on 100 the work-sheet of said margin stop, said scale forming a movable guide normally spaced from the platen for introducing work-sheets at the front of the platen, and movable toward the platen into position to 105 indicate on the work-sheet the printing line, and means for holding the said guide spaced from the platen while a work-sheet is being written upon.

5. In a front-strike typewriting machine, 110 the combination with a carriage and a rotatable platen, of a swinging plate adjacent said platen at one end of its travel and forming with the platen an inclined guide-way for the introduction of work-pieces to 115 the platen, said plate movable to bring its free edge in opposition to the printing line on the platen, a stationary support on which said plate normally rests so as to steady its edge, a handle for swinging said plate on 120 said support, and a stop limiting said swing.

6. In a front-strike typewriting machine, the combination with a carriage and a rotatable platen, of a swinging plate adjacent 125 said platen at one end of its travel, an apron for guiding paper around said platen, and means for moving said apron away from said platen so that it will aline with said plate, said plate being movable from a position in which its free edge alines with said 130

apron to a position in which said edge is at the printing line on the platen.

7. In a front-strike typewriting machine, the combination with a scale plate fixed on the frame of the machine, and a carriage pointer indicating on said scale, of a second scale plate carried by the frame for indicating a letter space on the platen, and movable into and out of position to form an intake chute for a work-sheet.

8. In a front-strike typewriting machine, the combination with a carriage and type printing thereon, of a scale plate on the frame at one side of said printing point for indicating a letter-space on said carriage, and normally in position to form an intake chute for a work-sheet, and a scale indicating the position of said carriage.

9. In a typewriting machine, the combination with an apron extending under the platen and fingers extending forward from said apron, of a chute extending toward said fingers, a swinging plate forming part of said chute, a scale on said swinging plate, and means to swing said plate upward to a substantially horizontal position with its edge at the lower edge of the printing line.

10. In a typewriting machine, the combination with a carriage, of a scale arranged to be swung adjacent thereto, an arm on which said scale is pivoted, screws for adjusting said arm vertically, and screws for adjusting said arm horizontally.

11. In a typewriting machine, the combination with a carriage, of a scale arranged to be swung adjacent thereto, an arm on which said scale is pivoted, screws for adjusting said arm vertically, screws for adjusting said arm horizontally, and an adjustable rest supporting the outer end of said arm.

12. In a typewriting machine, the combination with a paper apron, of a handle movable downwardly for depressing it, a scale forming with the depressed apron a chute for a work-sheet, and a handle movable downwardly for raising said scale to the printing line.

13. In a front-strike typewriting machine, the combination with a scale on the frame of the machine, of a pointer indicating on said frame the limit of travel of the carriage, a scale on the frame for indicating letter spaces on said carriage, a handle for swinging said second scale adjacent to the carriage, and a spring holding it normally away from said carriage in position to form a guide for inserting a work-sheet at the front of the platen.

14. In a front-strike typewriting machine, the combination with a scale on the frame of the machine, of a pointer indicating on said frame the limit of travel of the carriage, a platen on said carriage, a paper apron adjacent said carriage, a handle for

moving said apron away from said platen, a plate arranged to form a chute leading to said apron when away from said platen and movable to a horizontal position with its edge at the printing line on the platen, 70 and a scale on said plate.

15. The combination with a revoluble platen, a carriage therefor, and a releasable paper guide extending around the under side of the platen to the front portion thereof, of a chute mounted upon the machine frame in front of the carriage in position to coöperate with said paper guide only when the latter is released, said chute mounted for movement to the platen to serve as a line-gage for the work-sheet.

16. In a front-strike typewriting machine having a framework, the combination of a revoluble platen, a carriage for said platen, paper-guiding means extending around the under side of the platen to the front thereof, and a chute mounted upon the framework of the machine, the length of said chute being a greater portion of the length of the printing field on the platen, and displaced to one side of the printing point in position to be of use only when the carriage is at one extreme portion of its travel, said chute being mounted for moving to the platen to serve as a line-gage therefor.

17. In a front-strike typewriting machine having a framework, the combination of a revoluble platen, a carriage for said platen, paper-guiding means extending around the under side of the platen to the front thereof, and a chute mounted upon the framework of the machine, the length of said chute being a greater portion of the length of the printing field on the platen, and displaced to one side of the printing point in position to be of use only when the carriage is at one extreme portion of its travel, said chute being mounted for moving to the platen to serve as a line-gage therefor, and having a scale to serve correctly as a platen scale 100 only when the carriage is at the extreme end of its run.

18. In a front-strike typewriting machine, the combination with the framework of the machine, of a carriage thereon, a revoluble platen on said carriage, a paper-guiding device under the platen and movable downwardly away from the platen to release the work-sheet, and a paper-chute mounted upon the framework at the front of the 115 platen, the length of the chute being a greater portion of the length of the printing field on the platen, and displaced entirely to one side of the printing point, and capable of coöperation with said paper apron 120 when the latter is released and when the carriage is at one extreme of its travel.

19. In a front-strike typewriting machine, the combination with the framework of the machine, of a carriage thereon, a revoluble 130

- platens on said carriage, a paper-guiding device under the platen and movable downwardly away from the platen to release the work-sheet, and a paper-chute mounted upon the framework at the front of the platen, the length of the chute being a greater portion of the length of the printing field on the platen, and displaced entirely to one side of the printing point and capable of coöperation with said paper apron when the latter is released and when the carriage is at one extreme of its travel, said guide mounted to swing to the platen to serve as a line-gage.
20. In a front-strike typewriting machine, the combination with the framework of the machine, of a carriage thereon, a revoluble platen on said carriage, a paper-guiding device under the platen and movable downwardly away from the platen to release the work-sheet, and a paper-chute mounted upon the framework at the front of the platen, the length of the chute being a greater portion of the length of the printing field on the platen, and displaced entirely to one side of the printing point, and capable of coöperation with said paper apron when the latter is released and when the carriage is at one extreme of its travel, said guide mounted to swing to the platen to serve as a line-gage and provided with a scale which coöperates correctly with the platen only when the carriage is at the extreme end of its run.
25. 21. In a front-strike typewriting machine, the combination with a revoluble platen and a carriage therefor, of a plate mounted upon the frame of the machine and having a letter-supporting scale thereon, and normally in a position removed from the platen so that the scale is not usable, a support for said plate, and means for swinging said plate to the platen to serve as a line-gage and letter-space scale when the carriage is at a certain point in its travel.
22. In a front-strike typewriting machine, the combination with a revoluble platen and a carriage therefor, of a plate mounted upon the frame of the machine and having a letter-supporting scale thereon, and normally in a position removed from the platen so that the scale is not usable, a support for said plate, and means for swinging said plate to the platen to serve as a line-gage and letter-space scale when the carriage is at a certain point in its travel, said plate mounted to swing to and from the platen, and a stop being provided to limit the movement of the plate to the platen.
23. In a front-strike typewriting machine, the combination with a revoluble platen and a carriage therefor, of a plate mounted upon the frame of the machine and having a letter-supporting scale thereon, and normally in a position removed from the platen
- so that the scale is not usable, a support for said plate, and means for swinging said plate to the platen to serve as a line-gage and letter-space scale when the carriage is at a certain point in its travel, said plate mounted to swing to and from the platen, and a stop being provided to limit the movement of the plate to the platen, said plate when in normal position serving as a guiding apron or chute for introducing sheets backwardly at the front side of the platen.
24. In a front-strike typewriting machine, the combination of a scale plate fixed on the front of the machine, and a carriage pointer coöperating with the same to indicate the position of the carriage, a second plate also mounted upon the framework of the machine and having a scale, the length of said scale being a greater portion of the length of the printing field on the platen, and displaced entirely to one side of the printing center, and in position to correctly coöperate with the platen scale when the carriage is at one extreme of its run.
25. In a typewriting machine, the combination of a carriage, a platen on said carriage, a scale and index to show the position of the carriage, and a scale equal in extent to a major portion of the printing field on the platen, and mounted on the framework of the machine, and displaced entirely to one side of the printing point and mounted to coöperate with the platen correctly only when the carriage is at one extreme of its run.
26. In a front-strike typewriting machine, the combination with a machine frame, a carriage, and a platen thereon, of a plate hinged to the machine frame in front of the platen and extending downwardly and rearwardly from its hinge in position to form a guide for inserting work-sheets from the front of the platen, said plate movable upwardly to bring its edge to the printing line on the platen, and a scale on said plate.
27. In a front-strike typewriting machine, the combination with a carriage and a platen thereon, of a plate having a horizontal hinge and extending downwardly and rearwardly in position to form an intake chute for work-sheets introduced from the front of the platen, said plate mounted to swing upwardly to a substantially horizontal position, and means for arresting said plate with its edge at the printing line on the platen, so that said plate may serve as a line-gage for the work-sheet.
28. In a front-strike typewriting machine, the combination with a carriage and a rotatable platen, of a normally inclined swinging plate adjacent said platen at one end of its travel and forming a guide for the introduction of work-pieces to the platen, a stationary support on which said plate

- swings, and a scale on said plate to indicate letter-spaces, said plate movable to bring its free edge against the platen along the printing line while the platen is in normal position.
5. 29. In a front-strike typewriting machine, the combination with a carriage and a rotatable platen, of a normally inclined swinging plate adjacent said platen at one end of its travel and forming a guide for 10 work-sheets being placed on the platen, a stationary support for said plate, and a handle for said plate arranged to swing said plate and bring its free edge in opposition to the platen to indicate the position of a 15 writing line.
30. In a front-strike typewriting machine, the combination with a carriage and a rotatable platen, of a swinging plate adjacent the platen when the platen is at one 20 end of its travel, said plate being normally out of contact with the platen surface to permit the introductory passage of work-sheets, a stationary support for said plate,
- and a handle therefor arranged to swing said plate and bring its free edge toward the 25 platen to indicate the position of the writing line on the platen.
31. In a front-strike typewriting machine, the combination with a carriage and a rotatable platen, of a swinging plate 30 adjacent the platen when said platen is at one end of its travel, said plate being normally out of contact with the platen surface to permit the introductory passage of work-sheets, and movable to bring its free edge to 35 toward the platen to indicate the position of the writing line thereon, a stationary support against which said plate rests while so extended, a handle for swinging said plate on said support, and a stop to limit 40 the movement of said handle.
